UNITED STATES PATENT OFFICE.

MEADE WILDRICK, OF SAVANNAH, GEORGIA, ASSIGNOR TO W-H KEYLESS LOCK COMPANY, LIMITED, OF HONOLULU, TERRITORY OF HAWAII, A CORPORATION OF THE TERRITORY OF HAWAII.

KEYLESS LOCK.

Application filed November 4, 1924, Serial No. 747,777. Renewed November 27, 1925.

This invention relates to keyless locks of the general type shown in U. S. Patents No. 1,565,132, granted Dec. 8, 1925, and No. 1,577,398, granted Mar. 16, 1926; also shown and described in the application Serial No. 746,178, filed Oct. 27, 1924, by Meade Wildrick, entitled "Wheel for keyless locks", and has for one of its objects to provide a lock of this general character which will be simple in construction, comparatively inexpensive to manufacture and very efficient in action.

A further object of the invention is to provide a keyless or permutation lock, which may have a wide application to various uses, such for example, as to ignition locks, steering wheel locks, transmission locks, door locks and tool case locks, for automobiles; to baggage such as suit cases, trunks and brief cases; to builder's hardware such as door locks, pad locks and bolt locks such as are commonly used on lockers in country clubs, gymnasiums, coat rooms, etc.; to safes, safe deposit boxes and strong boxes and other similar containers; and to office equipment, such as filing cases and desk drawers.

With the above and other objects in view which will appear as the description proceeds, the invention consists in the novel details of construction and combinations of parts more fully hereinafter described and particularly pointed out in the appended claims.

Referring to the accompanying drawings, forming a part of this specification in which like reference characters designate like parts in all of the views:—

Figure 1 is a front elevational view of a bolt lock constructed in accordance with the present invention, such as would be particularly adapted for use upon locker doors and the like.

Figure 2 is a side elevational view of the lock shown in Figure 1 as seen from the right of the said figure.

Figure 3 is a vertical sectional view taken approximately on the plane indicated by the line 3—3 of Figure 2, looking in the direction of the arrow.

Figure 4 is a detail perspective view of the bolt employed in the lock shown in Figures 1, 2 and 3.

Figure 5 is a detail elevational view of one of the permutation wheels.

Figure 6 is an elevational view of a somewhat modified form of the invention illustrating the application of the generic principles to a baggage lock, such for example, as a trunk or suit case lock.

Figure 7 is a longitudinal sectional view through the lock shown in Figure 6, taken approximately on the plane indicated by the line 7—7 in said figure and

Figure 8 is a longitudinal sectional view at right angles to Figure 7, taken approximately on the plane indicated by the line 8—8 in said figure.

Referring more especially to Figures 1 to 5 inclusive, the numeral 10 indicates generally the lock casing or housing which may take the form of a hollow casting, the open rear end 11 of which may be closed by the plate 12, secured thereto by the screws 13 as clearly shown in Figure 2. The interior of the said casing is recessed as indicated at 14 to accommodate the working parts of the lock which comprise the bolt 15, and the permutation wheels 16. The said bolt 15 comprises a head 17 having the projecting portion 18 and axially extending shaft 19, which latter is provided with a plurality of pairs of circumferential grooves 20 and 21 as will be clear from the drawings. The said shaft is also provided with a longitudinally extending key-way 22 which preferably extends substantially the full length of the shaft and which is adapted to receive the lugs or projections 23 formed upon the inner circumference of the wheels or disks 16 as will be clear from Figures 3 and 5. The parts are so designed and assembled that the key-way 22 will permit of axial movement of the bolt relative to the wheels 16 with the lugs or projections 23 riding in the said key-way while the circumferential grooves 20 and 21 will permit of rotation of the wheels upon the shaft, when the lugs or projections 23 are in alignment therewith as will be readily understood.

In other words, when the bolt 15 is in either open or locked position, the circumferential grooves 20 or 21 are brought into alignment with the lugs 23 so that wheels may be freely rotated upon the shaft 19 and when they are so rotated, to move the said lugs 23 out of axial alignment with the key-way 22, the bolt will be prevented from movement in either direction. On the

other hand, when the wheels are set to such position, that the lugs 23 are in alignment with the longitudinal key-way 22, then the bolt may be moved from locked to open position and vice versa, as will be readily understood.

In order to accomplish the sliding longitudinal movement of the bolt, the head 17 thereof is provided with an elongated slot 10 or opening 25 through which projects a pin or stud 26 which carries at its outer end a finger piece 27 which finger piece is of course, located outside of the casing 10. The said stud 26 also rigidly carries adjacent the bolt head 17 a disk 28 which is provided with a radial slot 29 which receives a pin or projection 30 rigidly mounted in the head 17 as will be clear from Figure 4. It thus results that oscillatory movement of the finger piece 27 and its stud 26 will, through the pin and slot connection 29 and 30 produce longitudinal movement of the bolt within the casing.

Such longitudinal movement may obviously be accomplished in both directions, if desired, but it is preferred to rely on this manual operation of the bolt for movement in one direction only, i. e., to move the bolt from locked to unlocked position.

In order to move the bolt in the opposite direction, there is provided on the opposite end of the bolt, or shaft 19, a recess or bore 31, in which is seated a coil spring 32, one end of which abuts against the casing 10 as will be clear from Figure 3. The pressure of this spring will thus tend to force the bolt toward the right as viewed in Figure 3 to its locked position, from which it may be returned by the manual operating means above described, as will be readily understood. Of course, when the bolt is unlocked by the manual means and it is desired to retain it in such unlocked position, one or more of the wheels 16 may be rotated to bring the lugs 23 out of alignment with the key-way 22 whereupon the bolt will be held open.

If desired, means may also be provided for retaining the bolt in unlocked position without the turning of the wheel 16 and for this purpose I have illustrated in Figure 3, a flat spring 35, secured to the casing 10 as by the screw 36 and provided with a V-shaped free end 37 which is adapted to enter a V-shaped recess 38 provided in the head 17, as will be readily understood.

When this detent means is employed, the spring 35 will of course be of such strength as to overcome the force of the spring 32 and of course in this case it will be necessary to rely on the manual operating means 27 to start the bolt home when it is desired to move the latter to locked position. Of course, after the end 37 of the spring 35 has been dis-engaged from the notch 38, the force

of the spring 32 will cause the bolt to snap to locked position.

In order to provide against the picking of the lock by unauthorized persons, who might manipulate the manual operating means 27 to force the bolt 15 toward the left as viewed in Figure 3, while at the same time rotating the disks 16, until it could be told by the sense of touch that the lugs 23 had been brought into alignment with the key-way 22, I prefer to provide the walls of the circumferential grooves 20 with a plurality of recesses or false slots 40 which are arcuately spaced around the circumference of the shaft 19, but which extend only a short distance longitudinally of the same. It results from such a construction that if it is attempted to pick the lock in the manner above described, that it will be impossible to tell by the sense of touch when the lugs 23 have really been brought into alignment with the key-way 22, since the same sensation will be produced every time one of the lugs register with one of these false slots 40.

The wheels or disks 16 are preferably provided with reduced flanges 41, the outer circumferences of which are provided with a plurality of arcuately spaced notches 42 which are adapted to be engaged by suitable detent springs 43 for retaining the wheel in any desired positions.

Coming now to the form of the invention illustrated in Figures 6 to 8 inclusive it will be noted that the generic principles are the same and that these figures merely show the application of these principles to a lock of somewhat different application, i. e., a trunk or suit case lock. In this said form, the casing 50 is provided with a cover plate 51 which may be secured thereto in any suitable manner, preferably by means of rivets. The casing is hollowed out as indicated at 52 to receive the bolt 53 which bolt is provided with the longitudinal key-way 54 and with the pairs of circumferential grooves 55 and 56, similar to the grooves 20 and 21 shown in the previous form. The permutation wheels 57 rotatably mounted on the bolt 53 are provided with the lugs or projections 58 for entering the key-way 54 and the grooves 55 and 56 in the manner previously described.

In this instance however, the bolt 53 is provided with a substantially rectangular plate 59 which is secured thereto as by the screws 60 which carries the finger member 61 which projects above the plate as clearly shown in Figure 7 and which is adapted, when the bolt is in a locked position to engage the downwardly projecting stud or catch 62 carried by the hasp member 63 as is well known in this form of lock. The plate 59 also carries a rigid stud 64 which projects upwardly through an elongated slot 120

65 formed in the cover plate 51, and said stud carries at its upper end a suitable finger piece 66 by means of which the plate 59 and the bolt 53 may be moved longitudinally.

6 In this form of the invention, instead of employing the coil spring, such as the spring 32 as above described for moving the bolt in one direction, I may provide a flat leaf spring 67 one end of which is rigidly attached to the casing 50 and the other end of which is engaged by a lug 68 carried by the plate 59 (see Figure 8). This spring may be so disposed as to normally tend to move the bolt toward the left as viewed in Figure 8 or in other words, to the locked position.

15 It is obvious however, that if desired, the action of the spring might be reversed so as to move the bolt to unlocked position. If desired to introduce the anti-picking feature above described, false slots or recesses 20 may be provided around one face of the grooves 55 as is clearly shown in Figure 8. However, it will be understood that these false recesses are not essential and may be omitted if desired, as is also the case with the spring such as 67. In other words, the lock may be employed without the false recesses, but without the spring, or it may be employed with the spring and with the recesses, or it may be employed without either of them or with both of them. Furthermore, the spring 67 may be incorporated so as to move the bolt in either direction as may be desired.

25 While the generic principles embodied by the present invention have been shown as applied to only two different forms of invention it may be obvious that they may be readily incorporated in any of the various 30 types of lock mentioned at the outset with only such minor changes as occur to those skilled in the art, therefore it is not wished to be limited to the above disclosure except as may be required by the appended claims.

35 Having thus described my invention, what I claim as new is:—

1. In a keyless lock, a casing; a bolt member longitudinally slidably mounted in said casing, provided with a plurality of circumferential grooves arranged in pairs, and with a longitudinal keyway extending substantially the full length of said bolt, communicating with said grooves; and permutation discs rotatably mounted on said bolt member, each provided with a lug adapted to ride in a pair of said grooves and in said keyway.

2. In a keyless lock, a casing; a bolt member longitudinally slidably mounted in said casing, provided with a plurality of circumferential grooves and with a longitudinal keyway communicating with said grooves, the walls of certain of said grooves being provided with a plurality of arcuately spaced

recesses; and permutation discs rotatably mounted on said bolt member, each provided with a lug adapted to ride in said grooves and keyway, and to enter said recesses.

3. In a keyless lock, a casing; a bolt member longitudinally slidably mounted in said casing, provided with a plurality of circumferential grooves arranged in pairs, a wall of one of the grooves of each pair being provided with a plurality of arcuately spaced recesses, said bolt member being also provided with a longitudinal key way communicating with all of said grooves; permutation discs rotatably mounted on said bolt member, each provided with a lug adapted to be received in said grooves, keyway and recesses; a spring normally urging said bolt in such a direction as to bring the smooth walls of said grooves into contact with said lugs; and manually operable means for moving said bolt in the opposite direction.

4. In a keyless lock, a casing; a bolt member comprising a head and a rigid cylindrical shaft longitudinally slidably mounted in said casing, said shaft being provided with a plurality of circumferential grooves arranged in pairs, one wall of one groove of each pair being provided with a plurality of spaced recesses, said shaft being also provided with a longitudinal keyway communicating with all of said grooves; permutation discs rotatably mounted on said shaft, each provided with a lug adapted to be received in said grooves, keyway and recesses; and a spring normally urging said bolt toward locking position, thereby bringing the smooth walls of said grooves into contact with said lugs.

5. In a keyless lock, a casing; a bolt member comprising a head and a rigid cylindrical shaft, longitudinally slidably mounted in said casing, said shaft being provided with a plurality of circumferential grooves arranged in pairs, one wall of one groove of each pair being provided with a plurality of spaced recesses, said shaft being also provided with an axial bore and with a longitudinal keyway communicating with all of said grooves; permutation discs rotatably mounted on said shaft, each provided with a lug adapted to be received in said grooves, keyway and recesses, a spring seated in said axial bore normally urging said bolt toward locking position, thereby bringing the smooth walls of said grooves into contact with said lugs; and manual means for moving said bolt in the opposite direction.

6. In a keyless lock, a casing; a bolt member comprising a head and a rigid cylindrical shaft, longitudinally slidably mounted in said casing, said shaft being provided with a plurality of circumferential grooves arranged in pairs, one wall of one groove

of each pair being provided with a plurality of spaced recesses, said shaft being also provided with an axial bore and with a longitudinal keyway communicating with all of said grooves; permutation discs rotatably mounted on said shaft, each provided with a lug adapted to be received in said grooves, keyway and recesses; a spring seated in said axial bore normally urging said bolt toward locking position, thereby bringing the smooth walls of said grooves into contact with said lugs; and a manual means for moving said bolt in the opposite direction; and means for retaining said bolt in unlocked position 13 against the action of said spring.

7. In a keyless lock, a casing; a bolt member comprising a head having a notch, and a rigid cylindrical shaft, longitudinally slidably mounted in said casing, said shaft 20 being provided with a plurality of pairs of circumferential grooves, a wall of one groove of each pair being provided with a plurality of arcuately spaced recesses, said shaft being also provided with an axial bore 25 and with a longitudinal keyway communicating with all of said grooves; permutation wheels rotatably mounted on said shaft, each provided with a lug adapted to be received in said grooves, keyway and recesses; a spring seated in said axial bore normally urging said bolt toward locking position, thereby bringing the smooth walls of said 30 grooves into contact with said lugs; manual means for moving said bolt in the opposite direction; and a spring detent carried by said casing adapted to engage the notch in said bolt head, to retain said bolt in unlocked position against the action of said first mentioned spring.

40 8. A bolt for keyless locks comprising a substantially cylindrical shaft provided with a plurality of circumferential grooves arranged in pairs and a longitudinal keyway communicating with all of said grooves, said shaft being adapted to serve as a journal for a plurality of permutation wheels, and said grooves and keyway being adapted to accommodate lugs carried by said wheels.

50 9. A bolt for keyless locks comprising a substantially cylindrical shaft provided with a plurality of circumferential grooves and a longitudinal keyway communicating with all of said grooves, one wall of certain of said grooves being provided with a plurality of arcuately spaced recesses, said shaft being adapted to serve as a journal for a plurality of permutation wheels, and said grooves, recesses and keyway being

adapted to accommodate lugs carried by said wheels.

60 10. A lock comprising a locking member movable from an effective to an ineffective position, and vice versa, a set of permutation wheels having parts obstructing movement of said element from one of said positions to the other except when set in a predetermined relation, the parts of said set of wheels and of said locking element which cooperate to obstruct such movement comprising a series of lugs projecting from one 65 into engaging relations with a series of slotted circular abutments carried by the other, and the abutments which cooperate with said lugs in opposing such movement having, in their effective surfaces, a series of 70 relatively shallow spaced recesses the entrance portions of which conform in shape with the entrance portions of their slots, and motive means tending to move said locking member in a direction such as to 75 separate said lugs from the recessed surfaces of said abutments.

80 11. A permutation mechanism for a keyless lock comprising pairs of movement-obstructing elements, each pair consisting of an element having a stop and an element having a slotted abutment opposing relative lock-controlling movement between said elements except when said stop and the slot in 85 said abutment are in registration, a series 90 of recesses to serve as false slots in the surface of the abutment which opposes lock-releasing movement of said stop, and motive means tending to maintain said movement-obstructing elements separated.

100 12. A permutation mechanism for a keyless lock comprising pairs of movement-obstructing elements, each consisting of an element comprising a stop and an element comprising an abutment having a portion 105 providing a clearanceway for said stop, said stops and abutments comprising means opposing relative lock-controlling movement between the elements of said pairs except when said stops and clearanceways are in registration, series of recesses in the surfaces of said abutments which cooperate with said stops to oppose relative lock-releasing movement between said elements, thereby serving as false clearanceways, and motive means tending to maintain said movement-obstructing elements in relative positions such that said stops and recessed surfaces of said abutments will normally be held out of contact with each other.

110 MEADE WILDRICK.
